UNITED STATES PATENT OFFICE.

WILLIAM BURLINGAME, OF EXETER, NEW HAMPSHIRE.

DESIGN FOR A RADIATOR.

SPECIFICATION forming part of Design No. 21,234, dated December 15, 1891.

Application filed November 7, 1891. Serial No. 411,231. Term of patent 7 years.

To all whom it may concern:

- Be it known that I, WILLIAM BURLINGAME, a citizen of the United States, residing at Exeter, in the county of Rockingham, State of New Hampshire, have invented and produced a new and original Design for Radiators, of which the following is a specification, reference being had to the accompanying fac-simile print, forming part thereof.
- 10 Figure 1 is a side view of a section or loop of a radiator, showing my design; and Fig. 2 is a perspective view of a series of sections grouped to form a radiator, the design upon both sides of each loop being identical.
- 15 The radiator-sections are composed of two vertical panels 2, divided centrally and longitudinally by a small bead or rib 3. The prominent characteristic consists in providing ornamentation in the form of a conventionalized 20 hawthorn leaf 4 and buds 5. These figures extend the entire length of each panel, but only on that part of the surface between the rib and the outermost edge of each section, as shown. A similar ornamentation is placed 25 between the bead and the inner edge of each section, but only upon that portion near each end, leaving a smooth portion 6. The surface of the sides at the top of each section is

adorned with scrolls 7, of which the combined effect produces the appearance of a capital 30 of the Ionic order. At the lower part are placed scrolls 8, which harmonize with the configuration in the corresponding part of the section at its top. (See Fig. 2.) Both sides of each section or loop have the same 35 design as that shown in Fig. 1 of the accompanying print.

What I claim is—

The design for a radiator, comprising a group 40 of sections or loops each having similar panels with a dividing rib or bead longitudinally, consisting of ornamentation representing hawthorn leaves and buds continuously of the 45 length of said panels, with similar figures extending only in part from the top to the bottom, having scrolls at the top in imitation of an Ionic capital and scrolls at the base to harmonize with the scrolls above, as herein shown and described.

In testimony whereof I affix my signature in 50 presence of two witnesses.

WILLIAM BURLINGAME.
